Inventor,

J. H. Miller.

33rd *Chas. & Co.*
Elkhorn, Wis.

UNITED STATES PATENT OFFICE.

JOHN HENRY MILLER, OF RISING SUN, OHIO.

CEMENT-BLOCK MACHINE.

Application filed June 13, 1922. Serial No. 568,022.

To all whom it may concern:

Be it known that I, JOHN HENRY MILLER, a citizen of the United States, residing at Rising Sun, in the county of Wood and State 5 of Ohio, have invented a new and useful Cement-Block Machine, of which the following is a specification.

The device forming the subject matter of this application is an improvement in the 10 cement-block machine shown in Patent Number 844,457, granted to me on Feb. 19, 1907.

The cement block machine shown in the patent above alluded to comprises a compression member, and this invention 15 contemplates the provision of novel means for operating the compression member.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in side elevation, a device constructed in accordance with the invention, parts appearing in section; Figure 2 is an 35 elevation wherein the operating mechanism is viewed at right angles to the showing of Figure 1; Figure 3 is a section on the line 3—3 of Figure 1; Figure 4 is a section on the line 4—4 of Figure 2.

The device forming the subject matter of 40 this application is adapted to be used in connection with cement block machines of various sorts, but by way of illustration there is shown in the drawings, a few parts of the 45 device covered by my aforesaid Patent Number 844,457. The parts which are common to both the machine shown in this application, and the machine shown in the 50 patent will be passed over briefly, the numerals used being those employed in the patent.

The machine embodies a frame 10 carrying a standard 24 supporting a back plate 25 constituting part of a mold box. The frame 55 10 carries guide bars 29 supporting a bottom plate 30 having a projection 32. The

front plate of the mold box is marked by the numeral 33 and is pivoted to the bottom plate 30, the bottom plate supporting a pallet 43. The numeral 17 designates a 60 vertically movable core mounted for reciprocation in the pallet 43 and in the bottom plate 30, any suitable means 19 being supplied for imparting vertical movement to the pallet. A tamping or compression 65 plate 60 is shown, and has a hollow extension 61.

Passing to the detailed construction of the device which characterizes this present application over my aforesaid patent, the 70 numeral 1 marks a lever, fulcrumed at 2 on the standard 24. A flexible element 3 is connected to the outer end of the lever 1 and supports a counter-weight 4. The lever 1 embodies U-shaped extensions 5 connected 75 by a cross piece 6 having ears 7 whereunto a depending loop-shaped link 8 is pivoted as at 9 the link being adapted to engage the projection 32.

Upstanding guides 11 are mounted on 80 the hollow extension 61 of the compression plate 60 and are supplied with vertically elongated slots 12. The numeral 14 marks a shaft having cylindrical ends 15 and a polygonal intermediate portion 18. The 85 cylindrical ends 15 of the shaft 14 are received for sliding movement and for rotation in the slots 12 of the guides 11 and are rotatable in the extensions 5 of the lever 1. Securing elements 16 may be mounted in the 90 ends 15 of the shaft 14, outwardly of the guides 11.

The numeral 20 marks an operating member or handle, having forks 21 located between the extensions 5 of the lever 1 and 95 mounted on the polygonal intermediate portion 18 of the shaft 4, the construction being such that when swinging movement is imparted to the operating member 20, rotation will be imparted to the shaft 14. An eccentric 23 is carried by the polygonal intermediate portion 18 of the shaft 14 and is, therefore, rotatable with the shaft, when the shaft is rotated through the instrumentality of the operating member 20. The eccentric 23 100 operates within a strap or head 26, anti-friction devices, such as balls 27, being interposed between the eccentric and the strap or head. The eccentric 23 and the strap 26 lie between the forks 21 of the operating member 20, the strap or head 26 having a depending arm 28 mounted on a pivot element 110

31 carried by bosses 34 which project inwardly, toward each other, from the guides 11.

In practical operation, assuming that the 5 latch 8 is engaged with the projection 32, as shown in Figure 1, it will be obvious that when rotation is imparted to the shaft 14 by way of the handle 30, the eccentric 23 will be rotated, the radius arm, including the parts 28 and 26 being carried downwardly, when the handle 20 is swung in the direction of the arrow A in Figure 1, the compression member 16 moving downwardly and the ends 15 of the shaft 14 moving 10 downwardly in the slots 12 of the guides 11. The construction and operation of the device is such that a proper tamping of the material within the mold box, will be brought about.

15 The latch 8 may be cast off from the projection 32 and when the operating member 20 is swung in the direction of the arrow B in Figure 1, the lever 1 will swing on its pivotal mounting 2, the entire operating mechanism, including the compression element 60 being carried backwardly, away from the mold 5. The weight 4 acts as a counterpoise, and renders comparatively easy, the backward swinging movement of the compression member 60, and parts associated therewith, in the direction of the arrow B.

What is claimed is:—

1. In a device of the class described, a 35 frame; a lever fulcrumed intermediate its ends on the frame; a counterpoise weight assembled with one end of the lever; a latch forming a releasable connection between the other end of the lever and the frame; a shaft journaled in the lever; means for operating the shaft; an eccentric on the shaft; a compression member; a guide on the compression member and receiving the shaft 40 slidably; a strap surrounding the eccentric; and means for mounting the strap pivotally on the compression member.

45 2. In a device of the class described, a frame; a lever fulcrumed on the frame; a latch forming a releasable connection between the lever and the frame; a shaft journaled in the lever; means for operating

the shaft; an eccentric on the shaft; a compression member; a guide on the compression member and receiving the shaft slidably; a strap surrounding the eccentric; and means for mounting the strap for pivotal movement on the compression member. 55

3. In a device of the class described, a frame; a lever fulcrumed on the frame; a shaft journaled in the lever; means for operating the shaft; an eccentric on the shaft; a compression member; a strap surrounding the eccentric; and means for pivotally mounting the strap on the compression member. 60

4. In a device of the class described, a frame; a lever fulcrumed intermediate its ends on the frame; a counterpoise weight assembled with one end of the lever; a latch forming a releasable connection between the other end of the lever and the frame; a shaft journaled in the lever; means for operating the shaft; an eccentric on the shaft; a compression member; a strap surrounding the eccentric; and means for mounting the strap pivotally on the compression member. 70

5. In a device of the class described, a frame; a lever fulcrumed on the frame and including forks; a compression member; a handle having forks; a shaft comprising a polygonal intermediate portion, and cylindrical ends, the eccentric being mounted on the polygonal portion of the shaft, the forks of the handle being mounted on the polygonal portion of the shaft, the cylindrical ends of the shaft being slidable in the guides and being rotatable in the forks of the lever; a strap surrounding the eccentric and disposed between the forks of the handle; and means for mounting the strap for swinging movement on the compression member. 80

In testimony that I claim the foregoing 95 as my own, I have hereto affixed my signature in the presence of two witnesses.

JOHN HENRY MILLER.
